FILTER

Ralph Forbush Norris, Madison, Wis., assignor to
 C. F. Burgess Laboratories, Inc., Chicago, Ill.,
 a corporation of Delaware

Application November 9, 1934, Serial No. 752,246

8 Claims. (Cl. 183—45)

This invention relates to improvements in filters and in particular filters used for cleaning the intake air of internal combustion engines.

Among the objects of this invention are the providing of a highly efficient cleaner which has a high capacity, has a low air restriction, occupies a relatively small space and is relatively cheap to construct.

The following specification should be read in connection with the accompanying drawing in which:

Fig. 1 is a detailed view showing the construction of the gimped material of which the filter is made;

Fig. 2 is a sectional view of an annular cylinder filter unit incorporating the gimped material of Fig. 1;

Fig. 3 is a side elevation of a cross-wound cylindrical filter in which the carrier strands only are shown for clarity; and

Fig. 4 is a view similar to Fig. 1 showing a construction in which a plurality of gimped members are arranged upon a single carrier strand.

Air filters satisfactory for internal combustion engines and especially automobile engines should have the characteristics listed above. The filter of my invention has these characteristics.

The gimped material 10 of Fig. 1 is the basis of my improved filter body. It is made of a central flexible carrier strand 12 about which a second strand 14 is wound or gimped in the form of a helix. The strand 14 is made of a spring-like material so that the helix is substantially a helical spring along the length of carrier strand 12. The use of this springlike and resilient helix for the gimped material is a novel feature of my invention. Strand 14 is preferably made of metallic ribbon. Mechanically worked copper ribbon is usually used although aluminum, iron and any other metal or alloy may be used which has the desired physical properties or which may be either heat-treated or physically worked to give it the desired resiliency or springiness. Copper is the metal which is favored at present for automobile engine filters.

Excellent results are obtained with a filter body made as hereinafter described from a gimped material made of spring-like copper ribbon strands 0.025 inch wide by 0.0027 inch thick, the helical spring being 0.125 inch in diameter with 18 coils per inch of length. These dimensions are merely illustrative and my invention is not limited to gimped material made from copper ribbon of these dimensions.

Although the carrier strand 12 is indicated

as being made of metal ribbon, nevertheless it may be made of any suitable flexible material which may be ordinary wire, yarn, textile cord, or any textile fabric which is not too large in proportion to the helix.

The shape of the filter body is determined largely by the size, construction and location of accompanying equipment, such as, for example, the intake silencer of an automobile, which may be combined conveniently mechanically with the cleaner.

The gimped material, in the form of a strand, is usually assembled conveniently by winding it into a cylinder, ball, or other shape. It may be assembled by other methods as by packing it in heterogeneous arrangement instead of the orderly arrangement produced by winding. An annular cylinder as shown in Fig. 2 is used to a large extent for automobile intakes.

It is apparent that the type of winding also affects the characteristics of the finished cleaner. For example, winding under considerable tension results in a compact cleaner having small openings and a high restriction. The gimped material may be "spool-wound", which is the type of winding used on ordinary spools of thread. It may also be "cross-wound" as shown in Fig. 3, this type of winding being preferred.

The preferred cross-wound filter body of Fig. 3 shows a structure in which the strands of gimped material in any one layer are spaced apart. The adjacent coils in any layer preferably are spaced apart at least about the diameter of the coils except at the edges where overlapping occurs. This spacing of the strands when combined with a light tension produces a filter body that is highly efficient with the above described gimped material. The cross winding should be effected in such a manner that a honeycomb structure is not produced, that is, the strands in alternate layers should be staggered as indicated by strand 16 in Fig. 3 and should not be in alignment. As shown the layers are wound about a single axis of the frame. The direction of the air flowing through the filter thereby is changed frequently. A more homogeneous filter body also is produced thereby. The annular cylindrical filter body of Fig. 2 may be produced by cross winding in the absence of retaining side walls. Such side walls are necessary if spool winding is used in order to keep the strands from rolling outwardly. Furthermore, cross winding prevents bunching of the gimped material which is characteristic of spool winding and thereby produces a filter of uniform porosity. It is essential to

have a uniform air flow throughout the filter in order to obtain maximum cleaning efficiency.

The spring-like helical coils are stiff enough so that their shape is retained and they do not 5 collapse during fabrication into filters and during use after fabrication. Filters made of soft gimped material sag and gradually slump so that they become useless. Since the spring-like coils are 10 resilient and do not collapse and the layers stay spaced apart, the filter is resilient as a whole, it retains its shape and its interior retains the necessary large volume of voids. Filters of this 15 type are dipped in oil and drained before being put into service, the retained oil catching the dust passing through the coils. Each loop of the 20 coils of wire is an efficient retainer of oil since the oil gathers as a droplet at the bottom thereof. These coils therefore retain a large amount of oil which in turn catches a large 25 amount of dust. Because of the large number of loops and the large volume of voids the filter is capable of retaining a large quantity of dust before becoming clogged and it therefore has a high capacity.

25 Since the flexible carrier strand is relatively straight its oil retaining capacity is small if it is made of a single strand of metal. It therefore does not contribute greatly to the dust retaining capacity of the filter. Twine or cord or 30 similar absorptive material functions mechanically in a manner similar to metallic wire or ribbon when used as the carrier strand. However, it retains a relatively large amount of oil because of its wick-like properties and thereby 35 adds to the cleaning efficiency and dust capacity of the filter.

When the filter is made in the form of an annular cylinder the gimped material 18 is cross wound exteriorly on a cylindrical screen or cloth 40 20. A second cylindrical screen or cloth 22 is mounted exteriorly of the cross wound gimped material where it may be soldered in place. The exposed strands of gimped material at the ends of the cylinder catch readily on any projecting 45 points and therefore it is desirable to tie them in place to facilitate handling during assembly operations and during service. This is done by laying, before winding, four or more strands of gimped material 24 on the face of the inner cylinder 20, parallel to the axis thereof. These 50 strands, being longer than the cylinder, project beyond the end and are held in this position on the face of the inner cylinder when the filter is formed upon them. After the winding is completed the projecting ends of these tie strands 55 are turned over the ends of the annular cylinder of gimped material 18 as shown at 26 and held between the outer cylinder 22 and gimped material 18 when the outer cylinder is slipped into place.

60 In Fig. 4 of the drawing the gimped material 30 comprises a central flexible carrier strand 32, having a plurality of strands 34 wound or gimped thereon in the form of a helix. The 65 form shown in Fig. 4 consists of a pair of gimped strands arranged upon a single carrier strand, but it will be apparent that any number of strands may be gimped on the carrier strand. The gimped material of Fig. 4 possesses the 70 characteristics heretofore described in connection with Figs. 1 to 3 and it may be used in the construction of a filter body by winding it into the desired form as heretofore described in connection with Figs. 2 and 3 of the drawing.

The above specific example of my invention 5 illustrates the principles involved therein. It will be apparent to those skilled in the art that constructions may be used which vary in detail over a considerable range and that equivalent constructions may be used without departing from the scope of the following claims. Two or more strands of the gimped material 10 may be wound simultaneously to form the filter instead 10 of the single strand as described.

I claim:

1. A filter body comprising an interstitial structure of a plurality of overlying layers of strands of gimped material comprising a flexible carrier strand having one or more metallic 15 spring-like ribbons gimped thereon in the form of a continuous helical spring wound about said carrier strand throughout the length thereof, said strands of gimped material being wound upon a foraminous cylinder, the strands of 20 gimped material being cross wound, and the strands in any one layer being spaced apart.

2. A filter body in the form of an annular ring comprising overlying layers of cross-wound 25 strands of gimped material comprising a flexible carrier strand and one or more metallic spring-like strands gimped thereon in the form of a continuous helical spring wound about said carrier strand throughout the length thereof, said spring-like strands having sufficient stiffness to 30 retain their shape when in operation in a filter of the type herein described.

3. The filter body of claim 2 in which the carrier strand is under light tension and in which the spring-like strands are in the form of ribbon. 35

4. The filter body of claim 2 in which the strands of gimped material in any layer are spaced apart on the average a distance equal to at least the diameter of said helical spring.

5. The filter body of claim 2 in which the 40 strands of gimped material in any layer are spaced apart, and the strands in alternate layers are staggered to change the direction of the air flowing through the opening between said spaced apart strands.

45 6. A filter body comprising an interstitial structure of a plurality of overlying layers of one or more strands of gimped material comprising a flexible carrier strand having one or more metallic spring-like strands gimped thereon 50 in the form of a continuous helical spring wound about said carrier strand along the length thereof, the strands of gimped material in one layer extending crosswise of the strands in the adjacent layer and the strands in any one layer being 55 spaced apart.

7. A filter body comprising an interstitial structure of a plurality of overlying layers of one or more strands of gimped material comprising a flexible carrier strand having one or 60 more metallic spring-like strands gimped thereon in the form of a continuous helical spring wound about said carrier strand along the length thereof, the strands of gimped material in one layer extending crosswise of the strands in the adjacent 65 layer.

8. The filter body of claim 2 in the shape of an annular ring mounted between two telescoped foraminous cylinders, the gimped material being wound upon the exterior surface of the inner 70 cylinder.

RALPH FORBUSH NORRIS.
